UNITED STATES PATENT OFFICE.

AMANDUS L. LENTZ, OF TREICHLERS, PENNSYLVANIA, ASSIGNOR OF ONE-HALF TO
AUGUSTUS WOLF AND COMPANY, OF CHAMBERSBURG, PENNSYLVANIA.

SCREEN ATTACHMENT FOR ROLLING-MACHINES.

1,084,646.

Specification of Letters Patent. Patented Jan. 20, 1914.

Application filed May 8, 1912. Serial No. 695,949.

To all whom it may concern:

Be it known that I, AMANDUS L. LENTZ, a citizen of the United States, residing at Treichlers, in the county of Northampton and State of Pennsylvania, have invented a new and useful Screen Attachment for Rolling-Machines, of which the following is a specification.

This invention relates to improvements in screen attachments for rolling machines.

The primary object of the invention is to interpose a screen between the distributor and the grinding rolls of a rolling machine which will prevent foreign matter from being delivered to the rolls and which will deliver said material to the rolls, in a manner to produce a more uniform granulation of the stock than is possible, where the distributor, feeds directly on the rolls.

A further object of the present invention is to provide a screen which may be readily attached to rolling machines now in use and to so dispose the same that the operator may readily remove the foreign matter which is collected by the screen.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the drawings:—Figure 1 is an end elevation partly in section, of a common form of rolling machine, showing the screen disposed between the distributor and the grinding rolls. Fig. 2 is a perspective view of the screen.

In the drawings, 10 designates the rolling machine which receives stock through the spout 11 and delivers the same within the distributor 12. Normally the distributor 12 feeds the material to the rolls 14 and 15, the same being ground between the rolls and entering the hopper disposed at the base of the machine. Rolling mills of this type are provided with the sloping side wall 16 which is usually in the form of a plate or panel. In the present invention this plate or panel 16 is provided with a door 17 which opens at a point adjacent the delivery end of the dis-

tributer 12. The door 17 is hingedly supported to the portion 18 of the frame at the point 19, being lifted by means of the knob 20, and the lower portion of the door contacting with the plate 21 of the machine 60 frame. The screen 22 is secured to this plate 21. This screen is preferably formed of a concaved sheet of wire fabric, the gage of the wire and the texture of the same being determined by the quality of the stock handled by the mill. Screen 22 is secured to the bar 24 which serves as a reinforcing and attaching bar, this bar being secured to the portion 21 of the machine frame the screen being primarily above the roll 15 with its 65 inner free, resilient end extending beneath the delivery end of the distributor 12. It will be noted that the free end of the screen 22 is disposed in a horizontal plane which is higher than the plane of the concaved portion of the screen and is in substantially the same horizontal plane as the supporting strip 24, the free end acting as a means to prevent to a certain extent the crowding of the material thereover and thus confining 70 75 the material within the concaved portion so that as the same falls upon the screen it will be properly distributed through the meshes of the same during the resilient action imparted to the 80 screen by the falling of the stock. The stock descends through the spout 11 and is fed on the screen by the distributor 12. The falling stock tends to slightly shake the screen, due to the resiliency of the screen, so 85 that the screen automatically feeds the stock in a thin stream, the screen disintegrating and scattering the stock thereby permitting a more uniform granulation of the same than possible when the stock is fed to the 90 rolls from the distributor direct. It will be noted that by disposing a screen at this point all foreign matter such as dough balls, webs, or in fact any foreign material coming 95 through the spout will be prevented from 100 passing to the rolls, thus assuring an even rolling of the same, this reducing pressure on the rolls preventing the same from rolling during the grinding process. The bar not only acts as a reinforcing and supporting medium for the screen, but prevents the stock and tailings from pocketing against the panel 17, and as the greater portion of the screen is above the roll 15 and such roll rotates toward the center of the machine, 105 110

the stock falling primarily upon the roll 15 will be directed between both of the rolls. It has also been found that with a screen disposed at this point, in flour rolling mills, 5 the same serves as a means for whitening the flour, the finished product being of the same degree of whiteness as though nitrates had been used. This is due to the fact that the grain is supplied to the rolls in what 10 may be termed a thin misty stream. It will be noted that the foreign material may be removed from the screen or the screen removed for the purpose of cleaning in a simple and convenient manner, the retaining 15 strip 24 being secured to the portion 21 of the machine in any suitable manner which will retain the same against displacement during the operation of the mill and which will allow the same to be readily lifted out 20 of place when it is desired to remove it from the machine.

The many advantages of a construction of this character will be clearly apparent as it will be noted that the same may be readily 25 attached to rolling mills now in use without materially altering their construction and that the same will increase the efficiency of the mill in the actual rolling process and

will enable the grinding rollers to produce a finer product than heretofore produced, 30 without the use of nitrates or other bleaching chemicals.

What is claimed is:—

In a rolling mill, a supporting structure; 35 grinding mechanism; intermittently operating means for delivering material above the grinding mechanism; and a resilient, horizontally disposed close-mesh screen interposed between the grinding mechanism and the delivery means, the screen being 40 concaved to accumulate a load of material as the delivery means fluctuates in its operation, the screen being secured at one end only to the supporting structure, whereby the free end of the screen will vibrate under 45 the weight of the material and deliver the material to the grinding mechanism in an unvarying flow during the varying operation of the delivery means.

In testimony that I claim the foregoing as 50 my own, I have hereto affixed my signature in the presence of two witnesses.

AMANDUS L. LENTZ.
